FIRING RATE CONVERSION MEANS FOR AUTOMATIC FIREARMS

Richard H. Colby, South Hadley, Mass., assignor to the United States of America as represented by the Secretary of the Army

Filed May 5, 1958, Ser. No. 733,216

8 Claims. (Cl. 89—129)

(Granted under Title 35, U.S. Code (1952), sec. 266)

The invention described herein may be manufactured and used by or for the Government for governmental purposes without the payment of any royalty thereon.

This invention relates to automatic recoil-operated guns and is more particularly directed to guns of this type which can be fired at a high or low rate at the option of the operator. This application is a continuation-in-part of the application by Richard H. Colby for "Dual Rate Machine Gun," Serial No. 577,903, filed April 12, 1956, and now abandoned.

The growing complexity of modern warfare requires that every attempt be made to design weapons which can accomplish more than one type of mission. For example, it is highly desirable to be able to employ the same machine gun against ground personnel as well as against low-flying aircraft. However, in order to assure efficient operation against either of these two types of targets, the gun must be capable of reliable operation at both a low and a high rate of fire and must also possess suitable means for rapidly converting the gun from operation at one rate to the other. While various prior art weapons are capable of this dual operation, such feature has usually been accomplished through suitable mechanism for incrementally varying the rate of travel imparted to the recoiling parts. This is generally accomplished by some type of hydraulic, pneumatic, or resilient device which can be set to absorb more or less of the energy imparted to the recoiling parts of the gun. While successful variation in the rate of travel of the recoiling parts has been achieved in the prior art, considerable difficulty has been experienced in rapidly converting from one extreme rate of fire to the other without detrimental effect on the reliability and uniformity of operation.

Accordingly, it is an object of this invention to provide improved means for rendering an automatic recoil-operated gun capable of selective conversion between uniform high and low rates of fire.

It is a further object of the present invention to provide an automatic recoil-operated gun wherein the operation thereof can be readily converted between a high and a low rate of fire without providing a corresponding change in the rate of travel of the recoiling parts.

Still another object of this invention lies in the provision of an automatic recoil-operated gun wherein the operation thereof can be readily converted between a high and low rate of fire simply through the selective control of the distance to which the barrel is permitted to travel prior to unlocking the breech.

A more specific object of this invention is to provide a manually-operated selector device for effecting the direct conversion of an automatic recoil-operated gun between extreme high and low rates of fire without the necessity for operating the gun through any intermediate rates of fire.

The specific nature of the invention as well as other objects and advantages thereof will clearly appear from

2

a description of a preferred embodiment as shown in the accompanying drawings in which:

Fig. 1 is a longitudinal sectional view of the rear portion of the gun with the recoiling parts shown in the battery position;

Fig. 2 is a forward extension of Fig. 1 with the recoil conversion mechanism shown in the position for securing short recoil operation of the gun and being partially broken away to more clearly show the relationship of the component parts;

Fig. 3 is a view similar to Fig. 1 but with the recoiling parts shown shortly after the bolt has been unlocked from the barrel extension and immediately prior to the termination of the short recoil movement of the barrel;

Fig. 4 is a forward extension of Fig. 3 similar to Fig. 2 but showing the means for halting the rearward movement of the barrel to obtain short recoil operation of the gun;

Fig. 5 is a view similar to Fig. 1 but with the recoiling parts shown at the conclusion of long recoil movement with the bolt seared against counterrecoil movement and the barrel free to move forward and unlock from the bolt;

Fig. 6 is a forward extension of Fig. 5 similar to Figs. 2 and 4 but with the recoil conversion mechanism shown in the position for securing long recoil operation of the gun;

Fig. 7 is a plan view of the rear portion of the gun in partial section to show the recoiling parts at the conclusion of long recoil travel and to show the respective means for separately returning the bolt and the barrel to battery positions;

Fig. 8 is a cross-sectional view taken along line 8—8 of Fig. 7;

Fig. 9 is a cross-sectional view taken along line 9—9 of Fig. 7;

Fig. 10 is a cross-sectional view taken along line 10—10 of Fig. 2 to show the engagement of the lugs on the barrel extension with the internal lugs of the recoil control ring for effecting short recoil operation of the gun and also showing in phantom the separate housings for the respective bolt and barrel counterrecoil springs;

Fig. 11 is a view similar to that of Fig. 10 but with the mechanism for converting the recoil operation of the gun shown in the long recoil position and also showing the means for imparting the movement of the selector lever to the recoil control ring;

Fig. 12 is a cross-sectional view taken along line 12—12 of Fig. 6 with the recoil conversion mechanism in the long recoil position and showing the means for imparting the movement of the manual selector to the barrel buffer collar;

Fig. 13 is a cross-sectional view taken along line 13—13 of Fig. 6 to show the relationship between the stop shoulder on the barrel and the lugs on the barrel buffer sleeve when the selector has been rotated to the position for effecting long recoil operation of the gun and also to show the means for securing the bolt and barrel counterrecoil spring housings to the receiver; and

Fig. 14 is a fragmentary sectional view taken along line 14—14 of Fig. 7.

Referring now to the drawings, the gun to which the present invention is adapted is shown with a tubular receiver 14 inclosing a bolt assembly 16 and a recoiling barrel 18 having an extension 20 threadably secured to the rear end thereof as shown at 21 and securely locked together by a threaded stud 22. The forward end of receiver 14 is exteriorly threaded as shown at 23 in order to permit mounting of the gun to any suitable fixed support 25. Longitudinal ribs 33 are provided on opposite sides of barrel extension 20 as shown in Fig. 7 and are

adapted to slidably engage in correspondingly positioned rectangular ways 34 longitudinally formed along the interior wall surfaces of receiver 14.

Bolt assembly 16 essentially comprises a body 24 and a head 26 having a plurality of spaced apart interrupted rings 28 at the forward end thereof arranged for mating engagement with similarly formed locking segments 30 formed within the rear end of barrel extension 20. Bolt body 24 is provided with outwardly projecting rectangular ribs 32 on either side thereof adapted to slidably engage in receiver ways 34. The underside of bolt body 24 includes a notch 36 adapted to be engaged by the free end of a longitudinal sear lever 38 pivotally mounted at its opposite end in a suitable housing 40 fixedly secured to the floor of receiver 14. A spring 42 is located between the bottom of housing 40 and the underside of sear lever 38 to provide the bias necessary to continually urge such lever into position to engage in notch 36 for retaining bolt body 24 in the fully recoiled position. Sear lever 38 is suitably connected to a release mechanism (not shown) which is arranged to be actuated by the movement of barrel 18 into the battery position in a manner well known in the art.

Bolt head 26 is provided with oppositely projecting cylindrical studs 44 terminating in substantially rectangular end portions 46 arranged to slidably engage in receiver ways 34 subsequent to the unlocking thereof from barrel extension 20 during short recoil operation of the gun. However, inasmuch as bolt head 26 is not rotated relative to bolt body 24 when the gun is set for long recoil operation, a similar rectangular way 48 but of lesser depth is longitudinally disposed along each of the opposite interior wall surfaces of receiver 14 above one of ways 34 and below the other to slidably receive end portions 46 of bolt head studs 44. A substantially rectangular passage 50 is formed in both sides of receiver 14 to connect ways 48 and 34 and thereby provide a passageway for end portions 46 as bolt head 26 is rotated to unlock from the seared bolt body 24 when the gun is set for long recoil operation.

As best shown in Fig. 8, a camming insert 52 is pivotally mounted in a bifurcated bracket 53 projecting outwardly from the right side of receiver 14 and is arranged to normally extend into the interior of receiver 14 through a transverse slot 55 therein. Insert 52 is provided with a pair of adjacent longitudinal holes 57 therethrough arranged to selectively receive a pin 59 whose opposite ends extend into suitable openings in bracket 53. When pin 59 engages the outer one of holes 57, insert 52 is positioned to project into the interior of receiver 14 and thereby serves to cam bolt head 26 out of locked engagement with barrel extension 20 during the short recoil movement of bolt assembly 16. However, when long recoil operation of the gun is desired, pin 59 is withdrawn and insert 52 is pivoted outwardly to align the inner one of holes 57 with the pin openings in bracket 53. Pin 59 is then replaced to lock camming insert 52 in this pivoted position whereby bolt head 26 remains locked to barrel extension 20 during the entire recoil travel of bolt assembly 16 and consequently increases the time interval between each cycle of operation of the gun. A suitable buffer assembly 54 is provided in the rear end of receiver 14 to cushion and halt the recoiling travel of bolt assembly 16.

The forward end of receiver 14 is counterbored as shown at 56 and a cylindrical housing 58 is rotatably mounted therein and retained against forward movement by a barrel support collar 60 threadably secured to the front end of receiver 14. Collar 60 is formed with a forwardly tapering portion 62 having an axial bore 64 therethrough in which barrel 18 is slidably disposed for reciprocal longitudinal movement. Housing 58 is arranged to contain the spring assemblies required to control the recoil and counterrecoil movements of barrel 18 as will be hereinafter explained.

The forward half of barrel 18 is of slightly greater diameter than the rear half thereof and consequently forms an annular shoulder 66 for a purpose to be hereinafter shown. A plurality of longitudinal splines 68 are circumferentially spaced about the periphery of barrel 18 so as to terminate slightly rearwardly of shoulder 66. The height of splines 68 does not exceed the larger diameter of barrel 18 and therefore permits passage thereof through bore 64 of collar 60 during long recoil operation of the gun. Barrel 18 is also provided with a relatively shallow groove 70 extending longitudinally along the top thereof so as to receive the depending nose of a latch 72 pivotally secured to the forward end of receiver 14 and extending through a suitable vertical opening 73 therein. A spring 74 normally biases the nose of latch 72 into groove 70 thereby preventing any rotation of barrel 18 relative to receiver 14. The breech end of barrel 18 is longitudinally cut away as best shown at 76 in Fig. 5 and the cylindrical configuration of barrel extension 20 is similarly cut away at the top thereof to the extent necessary to bring the opposing free ends formed thereby into transverse alignment with the flattened portion 76 of barrel 18 as best shown in Figs. 10 and 11. As a result of the foregoing construction, barrel 18 and barrel extension 20 are adapted to reciprocate without interference by the underside of a cartridge feed tray 78 fixedly mounted into the top of receiver 14.

Barrel extension 20 extends forwardly beyond the area of locking engagement with barrel 18 to form a reduced diameter section 80 having a plurality of spaced apart, radially disposed lugs 82 projecting outwardly from the extreme forward end thereof. Correspondingly positioned lugs 84 are provided about the interior bore surface of a recoil control ring 86 which is slidably disposed within barrel control housing 58 for reciprocal longitudinal movement. However, rotation of ring 86 in housing 58 is prevented by a pair of pins 88 which are fixedly secured in opposite sides of ring 86 and project outwardly therefrom to extend into correspondingly disposed longitudinal slots 90 within housing 58 as shown in Figs. 10 and 11. Thus, when the rotation of housing 58 is imparted to ring 86 in a manner to be hereinafter shown, lugs 84 therein are either positioned in axial alignment with lugs 82 on barrel extension 20 or are disposed therebetween depending upon the direction in which housing 58 has been rotated. In the first mentioned position, the recoil travel of barrel extension 20 is imparted to ring 86 by the engagement between lugs 82 and 84 while in the second mentioned position lugs 82 pass between lugs 84 to permit the long recoil travel of barrel 18 and the extension 20 thereon.

Barrel control housing 58 is provided with an internal flange 92 arranged for contact by a forwardly facing annular shoulder 93 on the exterior of ring 86 for halting the forward movement thereof. Flange 92 is of sufficient depth to receive the projecting threaded end 94 of a screw 96 slidably disposed in a counterbored hole 102 extending vertically through a lever 99. As best shown in Figs. 2 and 10, lever 99 is a part of a selector assembly 98 and is provided with a knob portion 100 at the upper end thereof. A spring 104 is arranged to be compressed between the head portion of screw 96 and an annular shoulder 106 formed in hole 102 and thereby serves to normally urge the underside of selector lever 99 into contact with the exterior surface of barrel control housing 58. Receiver 14 is provided with a transverse slot 108 which is substantially equivalent in width to the diameter of screw 96 and terminates at either end thereof in enlarged semicircular openings 110 arranged to slidably receive the cylindrical lower end of selector lever 99. Thus, in order to rotate lever 99 between the settings for short and long recoil operation of the gun, knob portion 100 is raised against the bias of spring 104 out of engagement with one of the semicircular ends 110 in receiver 14 and is then rotated into alignment

with the other semicircular end 110 for engagement thereof upon being released.

Barrel control housing 58 is provided with an annular retainer 112 threadably secured into the rear end thereof and arranged to provide a seat for the rear end of a barrel recoil spring 114 which surrounds barrel 18 and its extension 20 and normally biases recoil control ring 86 forwardly against the rear surface of flange 92 in barrel control housing 58.

A barrel buffer collar 116 is slidably disposed within barrel control housing 58 for contact with the forward face of flange 92. The forward end of housing 58 is provided with an exteriorly threaded annular barrel buffer retainer 118 having a counterbored opening 120 therethrough arranged to form a rearwardly facing annular shoulder 122. Collar 116 and retainer 118 serve to slidably support a barrel buffer sleeve 124 arranged to surround barrel 18. A pair of diametrically opposed pins 126 are fixedly mounted in collar 116 and project beyond the exterior and interior surfaces thereof as best shown in Fig. 12. The outer ends of pins 126 extend into correspondingly located longitudinal grooves 128 formed in the inner periphery of barrel control housing 58. The inner ends of pins 126 extend through correspondingly located longitudinal slots 130 formed into barrel buffer sleeve 124 from the rear end thereof. Thus, pins 126 serve to transmit rotational movement of barrel control housing 58 to the barrel buffer sleeve 124.

The forward end of sleeve 124 is provided with an exterior annular flange 132 arranged to slidably extend into counterbored opening 120 for contact with shoulder 122 therein. A plurality of spaced apart lugs 134 are radially disposed about the interior periphery of sleeve 124 adjacent the forward end thereof and are arranged during short recoil operation of the gun for contact with the rear ends of splines 68 to assist in halting the recoil movement of barrel 18. Such buffering action is preferably accomplished through the snubbing action produced between an inner and an outer set of ring springs 136 and 138 respectively, which are slidably mounted on barrel buffer sleeve 124 between flange 132 thereon and barrel buffer collar 116.

The front and rear ends of receiver 14 are each provided with a pair of oppositely disposed outwardly extending mounting lugs 140. As best shown in Figs. 8 and 13, each of lugs 140 is of substantially rectangular configuration and is rectangularly slotted as indicated at 142 to transversely receive a similarly formed mounting stud 144 extending longitudinally from the front and the rear ends of a tubular housing 146 forming a component part of a barrel counterrecoil spring assembly 145 positioned on the right side of receiver 14. A headed pin 149 extends vertically through each lug 140 and stud 144 assembled thereto to releasably lock housing 146 against rotational movement relative to receiver 14.

Assembly 145 includes a cylinder 152 slidably disposed in housing 146 on a fixed guide rod 154 extending between the front and rear ends of housing 146. The front end of cylinder 152 is formed to provide a front seat 156 for a spring 158. A transversely projecting lug 160 at the rear end of cylinder 152 extends through a suitable longitudinal slot 162 along the side of receiver 14 and fits into a suitable vertical slot 163 cut into rib 33 on the right side of barrel extension 20. During the long recoil movement of barrel 18 and extension 20 thereon, sufficient energy is accumulated in spring 158 to return these parts to the battery position shown in Figs. 1 and 2.

A similar spring assembly 147 is similarly mounted between lug 140 on the left side of receiver 14 so that lug 160 on the rear end of the cylinder 152 is arranged to extend into a rectangular slot 170 vertically cut into the rectangular rib 32 on the left side of bolt head 24. As a result of such construction, spring assembly 147 serves to return bolt assembly 16 to the battery position during both long and short recoil operation of the gun. When

the gun is set for short recoil operation, the return of barrel 18 to the battery position is accomplished by recoil spring 114 and ring springs 136 and 138 before counterrecoil spring assembly 145 has been actuated to any appreciable extent.

In order to operate the gun in short recoil, camming insert 52 is pivoted into the interior of receiver 14 so as to project into the path of bolt head stud 44 and is locked in such position by pin 59. If the gun had been previously set for long recoil operation, selector lever 99 must be disengaged from the semicircular opening 110 in one end of receiver slot 108, as shown in Fig. 11, and rotated into position to engage in the semicircular opening 110 at the opposite end of slot 108, as shown in Fig. 10, in the manner hereinbefore described. This rotative movement of selector lever 99 is transmitted to barrel control housing 58 by screw 96 and the rotation of housing 58 is in turn transmitted to recoil control ring 86 through pins 88. In the short recoil position of ring 86, lugs 84 therein are positioned in respective axial alignment with lugs 82 on the forward end of barrel extension 20. At the same time, the rotation of barrel control housing 58 also serves to rotate barrel buffer sleeve 124 and bring lugs 134 therein into axial alignment with the rear ends of splines 68 on barrel 18.

Upon the firing of a cartridge, bolt assembly 16, barrel extension 20 and barrel 18 recoil as a unit until roller stud 44 on the right hand side of bolt head 26 strikes camming insert 52 and is rotated out of locking engagement with barrel extension 20, as shown in Fig. 3. As barrel extension 20 begins to recoil, lugs 82 at the forward end thereof engage lugs 84 within recoil control ring 86 and impart a corresponding rearward movement thereto which compresses spring 114 to eventually halt the recoil movement of the barrel assembly. During the recoil movement of the barrel assembly, the rear ends of splines 68 on barrel 18 contact lugs 134 within the interior of barrel buffer sleeve 124 and impart limited recoil movement thereto. Inasmuch as springs 136 and 138 are seated against collar 116 which is fixed against rearward movement due to the abutment thereof with annular flange 92 in barrel control housing 58, the resulting snubbing action of ring springs 136 and 138 not only aids in halting the recoil movement of barrel 18 but also accumulates sufficient energy to return such barrel to the battery position thereof.

Bolt assembly 16, however, continues to recoil in receiver ways 34 and compress counterrecoil spring assembly 147, as shown in Fig. 7, so that when the recoil movement of bolt assembly is finally halted by buffer assembly 54, the energy accumulated by spring 158 is sufficient to return the bolt assembly 16 to the battery position thereof. The final locking movement of bolt head 26 during movement into battery position is, of course, effected by the inertia mass of the forwardly moving bolt body 24.

In order to convert the gun to long recoil operation, camming insert 52 is pivoted to the position shown in Figs. 8 and 14 and selector lever assembly 98 is pivoted to the position shown in Fig. 11. In this position of selector lever 99, recoil control ring 86 has been rotated so that lugs 84 therein will permit the passage therebetween of lugs 82 on the forward end of barrel extension 20. This rotation of recoil control ring 86 also serves to rotate barrel buffer sleeve 124 so as to position lugs 84 therein out of the path of movement of splines 68 on barrel 18.

Thus, upon recoil movement of bolt assembly 16 in response to the firing of a cartridge in barrel 18, the locking engagement between bolt head 26 and barrel extension 20 will continue during the entire recoil movement thereof. The recoil energy of bolt assembly 16 is considerably reduced as shoulder 66 on barrel 18 contacts lugs 134 within barrel buffer sleeve 124 immediately prior to contact of bolt assembly 16 with buffer assem-

bly 54 and produces a snubbing action between ring springs 136 and 138. Roller studs 44 on bolt head 26 are arranged to travel in receiver ways 48 while ribs 32 on bolt body 24 simultaneously travel in ways 34. When bolt assembly 16 strikes buffer assembly 54 and begins the counterrecoil travel thereof, sear lever 38 engages sear notch 36 in the underside of bolt body 24 and prevents the forward movement thereof. However, bolt head 26 continues to counterrecoil together with barrel 18 and in doing so is rotated to unlock from barrel extension 26 so that roller studs 44 on bolt head 26 pass through passages 50 in the opposite sides of receiver 14 and cause rectangular ends 46 to engage in receiver ways 34. Barrel 18 is returned to battery position under the urging of ring springs 136 and 138 and of counterrecoil spring assembly 145 and at the conclusion of such movement sear lever 38 is actuated by means (not shown) to release bolt assembly 16 therefrom for return to battery position under the urging of counterrecoil spring assembly 147.

It is apparent that this considerably longer recoil and counterrecoil movement of barrel 18 requires a much longer firing cycle and therefore provides an appreciable reduction in the rate of fire of the gun in comparison to that encountered during the short recoil operation. Selection between these two rates of fire can be easily and rapidly effected merely through the proper positioning of camming insert 52 and the manipulation of selector lever assembly 98. Thus, in the event a change of targets requires a change in the firing rate of the gun, the new rate can be immediately obtained without the necessity for gradually bridging the appreciable gap between these two rates of fire. As a result of such rapid conversion between the low and high rates of fire, the unreliable and erratic operation generally found to occur in the prior art during a gradual attainment of the minimum or maximum rate of fire is effectively eliminated.

Although a particular embodiment of the invention has been described in detail herein, it is evident that many variations may be devised within the spirit and scope thereof and the following claims are intended to include such variations.

I claim:

1. In a recoil operated firearm having a receiver, a recoiling barrel, an extension fixedly secured to the breech end of the barrel, a bolt slidably mounted in the receiver for reciprocal movement between recoil and battery positions, and means on the barrel extension for releasably locking the bolt thereto for joint recoil movement, the combination of a plurality of outwardly projecting lugs radially spaced about the forward end of the barrel extension, a longitudinally slidable recoil control ring rotatably disposed in the receiver to encircle the barrel extension forwardly of the bolt locking means thereon, said ring having a plurality of projecting lugs radially disposed about the inner periphery thereof in spaced correspondence with said barrel extension lugs, a recoil spring surrounding the barrel extension to seat against said recoil control ring and resist the rearward movement thereof, selector means for rotating said recoil control ring prior to the discharge of the firearm to position said lugs thereon into and out of the recoil path of said barrel extension lugs, and cam means pivotally mounted in the receiver for movement into and out of the path of the bolt, said recoil spring being thereby utilized to halt the recoil movement of the barrel during the continued recoil movement of the bolt only when said recoil control ring lugs are positioned for contact with said barrel extension lugs and said cam means is positioned to unlock the bolt from the barrel extension.

2. In a recoil operated firearm, the combination of a recoiling barrel, an extension fixedly secured to the breech end of said barrel, a bolt slidably mounted in said receiver for reciprocal movement between recoil and battery positions, means on said barrel extension for re-

leasably locking said bolt thereto for joint recoil movement, a plurality of outwardly projecting lugs radially spaced about the forward end of said barrel extension, a cylindrical housing rotatably disposed in the forward end of said receiver, a recoil control ring slidably disposed in said housing to encircle said barrel extension forwardly of said bolt locking means thereon, said ring having a plurality of projecting lugs radially disposed about the inner periphery thereof in spaced correspondence with said barrel extension lugs, a recoil spring surrounding said barrel extension to seat against said recoil control ring and resist the rearward movement thereof, selector means for rotating said cylindrical housing in either direction, means for connecting said recoil control ring to said housing for rotation therewith whereby rotation of said housing in one direction positions said lugs on said ring for engagement with said lugs on said barrel extension to compress said recoil spring for halting the recoil movement of said barrel during the continued recoil movement of said bolt and whereby rotation of said housing in the opposite direction positions said recoil control ring lugs out of the path of said barrel extension lugs, spline means on the exterior periphery of said barrel, buffer means slidably disposed in said cylindrical housing forwardly of said recoil control ring therein for engagement by said spline means on said barrel to assist said recoil spring in halting the recoil movement of said barrel, and cam means pivotally mounted in the receiver for movement into and out of the recoil path of said bolt, said recoil spring and said buffer means being thereby utilized to halt the recoil movement of said barrel during the continued recoil movement of said bolt only when said recoil control ring lugs are positioned for engagement by said barrel extension lugs, said buffer means is positioned for engagement by said spline means on said barrel, and said cam means is positioned to unlock said bolt from said barrel extension.

3. In a recoil operated firearm having a receiver, a recoiling barrel, an extension fixedly secured to the breech end of the barrel, a bolt slidably mounted in the receiver for reciprocal movement between battery and recoil positions, and means on the barrel extension for releasably locking the bolt thereto for joint recoil movement, the improvement of means for converting the firearm between fast and slow rates of fire comprising, in combination, a plurality of outwardly projecting lugs radially spaced about the forward end of the barrel extension, a cylindrical housing rotatably disposed in the forward end of the receiver, a recoil control ring slidably disposed in said housing to encircle the barrel extension forwardly of the bolt locking means thereon, said ring having a plurality of projecting lugs disposed about the inner periphery thereof in spaced correspondence with said barrel extension lugs, a recoil spring surrounding the barrel extension to seat against said recoil control ring and oppose the rearward movement thereof, a longitudinally slidable sleeve rotatably disposed in said cylindrical housing forwardly of said recoil control ring therein, a plurality of projecting lugs radially spaced about the inner periphery of said sleeve, a plurality of longitudinally extending splines circumferentially disposed about the exterior periphery of the barrel in spaced correspondence with said lugs on said sleeve, ring spring means on said sleeve for opposing rearward movement thereof, cam means pivotally mounted in the receiver for unlocking the bolt from the barrel extension during recoil, said recoil spring and said ring spring means being thereby utilized to halt the recoil movement of the barrel during the continued recoil movement of the bolt whereby the firearm is operated at a fast rate of fire, means for rendering said cam means inoperative, pin means connecting said recoil control ring and said sleeve to said housing for rotation therewith, and a selector for rotating said housing to simultaneously position said lugs on said recoil control ring and on said sleeve out of the respective paths of said lugs

on the barrel extension and said splines on the barrel and thereby permit uninterrupted joint recoil movement of the barrel and bolt when said cam means is rendered inoperative whereby the firearm is operated at a slow rate of fire.

4. The combination defined in claim 3 including resilient means for counterrecoiling the barrel and the bolt into battery positions when said selector means is positioned to permit uninterrupted joint recoil movement thereof, said resilient means comprising a tubular housing fixedly secured to each side of the receiver, a guide rod extending between opposite ends of each of said tubular housings, a cylinder slidably mounted on said guide rod, a spring seated in said cylinder to oppose rearward movement thereof, and a fixed lug adjacent the rear end of each of said housings projecting into the receiver, one of said lugs engageable with the bolt to impart forward movement thereto, and the other of said lugs engageable with the barrel extension to impart corresponding forward movement thereto.

5. The combination defined in claim 3 wherein said cam means for unlocking the bolt from the barrel extension comprises a bracket fixedly secured to one side of exterior surface of the receiver, a camming insert pivotally mounted to said bracket and having an inner and an outer longitudinal hole therethrough, and a replaceable pin extending through said bracket and one of said holes in said camming insert whereby the engagement of said pin in said outer hole therein positions said insert to project into the interior of the receiver for rotating the recoiling bolt out of locked engagement with the barrel extension while the engagement of said pin in said inner hole positions said insert outwardly of the recoil path of the bolt to permit uninterrupted recoil movement thereof jointly with the barrel.

6. In a recoil operated firearm having a receiver, a recoiling barrel, an extension fixedly secured to the breech end of the barrel, a bolt slidably mounted in the receiver for reciprocal movement between battery and recoil positions, and means on the barrel extension for releasably locking the bolt thereto for joint recoil movement, the improvement of means for selectively converting the firearm between short recoil operation wherein the recoil movement of the barrel is limited to a distance slightly less than the length of the cartridge to be fired therein and long recoil operation wherein the recoil movement of the barrel is equivalent to that of the bolt and is greater than the length of the cartridge, comprising a cylindrical housing rotatably disposed in the forward end of the receiver and having a longitudinal bore therethrough for passage of the barrel and barrel extension, a recoil control ring slidably disposed in said housing to encircle the barrel extension forwardly of the bolt locking means thereon, a plurality of outwardly projecting lugs radially spaced about the forward end of the barrel extension, a plurality of correspondingly spaced lugs disposed about the inner periphery of said recoil control ring, a recoil spring surrounding the barrel extension and seated against the rear face of said ring to oppose rearward movement thereof, a circular flange disposed in the interior of said cylindrical housing to block forward movement of said recoil control ring, a collar fixedly secured within the interior of said cylindrical housing forwardly of said circular flange therein to encircle the barrel forwardly of said recoil spring, a sleeve disposed in said housing with the rear end thereof in slidable engagement with said collar, an annular re-

tainer fixedly secured in the forward end of said housing to block forward movement of said sleeve therein, said sleeve having an annular shoulder formed about the exterior of the forward end thereof, an inner and outer ring spring surrounding said sleeve between said annular shoulder thereon and said collar for opposing rearward movement thereof, a plurality of projecting lugs radially spaced about the inner periphery of said sleeve, a plurality of longitudinally extending splines circumferentially disposed about the exterior periphery of the barrel in spaced correspondence with said lugs on said sleeve, cam means pivotally mounted in the receiver for unlocking the bolt from the barrel extension during the recoil movement thereof, means for rendering said cam means inoperative, said recoil spring and said ring springs being thereby utilized to halt the recoil movement of the barrel for effecting short recoil operation of the firearm, pin means connecting said recoil control ring and said sleeve to said housing for rotation therewith, an exteriorly projecting selector lever fixedly secured to said cylindrical housing for imparting rotation thereto, means for latching said selector lever in a first position wherein said recoil control ring lugs are in the recoil path of said barrel extension lugs and said lugs on said sleeve are in the recoil path of said barrel splines to halt the recoil movement of the barrel during the continued recoil movement of the bolt and thereby provide short recoil operation of the firearm, and means for latching said selector lever in a second position wherein said recoil control ring lugs and said lugs in said sleeve permit uninterrupted joint recoil movement of the barrel and bolt when said cam means for unlocking the bolt from the barrel is inoperative and thereby provide long recoil operation of the firearm.

35. 7. The combination defined in claim 6 including an annular shoulder on the barrel forwardly of said longitudinal splines thereon for engaging said lugs within said sleeve to reduce the recoil energy of the bolt upon the conclusion of the long recoil movement thereof.

40. 8. The combination defined in claim 6 wherein the receiver is provided with a transverse slot terminating in enlarged ends, said selector lever is provided with a vertical counterbored hole, and said means for latching said selector member comprises a screw having an enlarged head and slidably disposed in said counterbored hole with the threaded end thereof projecting through said transverse slot in the receiver to engage in said cylindrical housing, and spring means seated between the bottom of said counterbored hole and said enlarged head on said screw to normally urge said lever into engagement with one of said enlarged ends of said transverse slot in the receiver, said lever being convertible from one enlarged end of said transverse slot to the other for rotating said cylindrical housing accordingly.
